UNITED STATES PATENT OFFICE.

MAX SOMMER, OF ESSEN-RUHR, GERMANY.

COKING RETORT OVEN.

Application filed October 11, 1923, Serial No. 668,027, and in Germany September 25, 1922.

- My invention refers to coking retort ovens having coking chambers arranged side by side, with intermediate heating walls and reversible regenerators serving said walls.
- 5 More particularly my invention relates to coking retort ovens of the Koppers type having a separate regenerator for each pair of heating walls.
- It is an object of my invention to increase 10 the heating efficiency and operating facilities of coking retort ovens of the above type. As is well known to those skilled in the art, in coking retort ovens of this type with vertical heating flues and alternate reversal of 15 the direction of the heating gases, the upper horizontal or bus flue connecting the upper ends of the vertical heating flues gives rise to disturbances in the uniform distribution of the heating gases over the entire surface of the heating wall. For reasons of 20 construction, the cross sectional area of this flue can be only comparatively small and nevertheless the exhaust gases from all the heating flues on one side of the oven must 25 be given free passage through it. Now, the quantities of such exhaust gases will be especially great in the case where the oven is heated with poor gas, because poor gas, such as ordinary producer gas, is laden with 30 incombustible particles. The same applies in the case where the oven is heated with coke oven gas diluted with smoke gas in order to adapt the operation of the oven to poor gas heating, as in such a case the smoke 35 gas also carries with it such incombustible particles.
- In order to dispense altogether with the upper horizontal flues, it has been proposed by several designers of coke oven batteries 40 to conduct the exhaust gases from the heating flues on one side of a coking chamber across this chamber to the heating flues on the other side of this chamber. Amongst others, the well known Munich type of coke 45 ovens with obliquely extending coking chambers is built on this plan. However, in order to cause the exhaust gases to thus pass across the coking or distillation chamber, longitudinal partitions must be provided 50 within each individual regenerator. Inasmuch, now, as on one side of such a partition, which, as a rule, is about 10-11 meters long and about 3 meters high, the gases flow upwards and on the other side downwards, 55 considerable differences of pressure occur on the different sides of this partition, ranging from 8 to 15 millimeters water column. Moreover, the brickwork in the lower portion of the regenerators expands much less than the walls mounted thereon and, in consequence thereof, these expansions give rise to fissures in the partition which allow gases to pass through from one side to the other. Owing to the arrangement of this partition, the regenerator chambers become so narrow as to be almost inaccessible. If the necessity arises of inspecting the walls, not only the checker work, but also one of the walls must be removed in order to get access to the adjoining wall or partition.
- In order to overcome these drawbacks, I combine a number of coking ovens of the well known Koppers type, having each a separate regenerator, into a group or unit 60 by means of passage ways extending on top of and at right angles to the oven chambers in such way, that in each group a plurality of heating walls is simultaneously heated in upward direction, the exhaust gases being led across the chambers and downwards in contact with an equal number of adjoining walls connected in parallel. By thus subdividing a battery of coke ovens into groups of four, six or eight ovens each, only a single partition extending longitudinally of 65 a regenerator is required in the middle and one at either end of each group or rather intermediate two such groups, the gases rising on one side and descending on the other side of this partition, pressure below the 70 normal always prevailing in the direction towards the chimney. The other regenerators of each group are unobstructed by partitions and can easily be inspected after the checker work is removed. I further cause 75 two adjoining groups or units to be operated in such a way that the gases always travel on either side of the partition separating such groups in the same direction. I thus prevent greater differences of pressure from 80 arising at these partitions.
- In the drawings affixed to this specification and forming part thereof, a coking retort oven embodying my invention is illustrated diagrammatically by way of example. 85 In the drawings
- Fig. 1 is a vertical transverse section of the upper part of the oven showing a row of heating flues with the passageways extending on top of and across a group of 90 ovens.
- Fig. 2 is a vertical longitudinal section of 95

a number of coking chambers, rows of heating flues and regenerators assembled into a self-contained group or unit, showing also the partition in the middle regenerator subdividing the group in two halves and the partitions at either end separating this group from other groups adjoining it.

Fig. 2^a is a diagram showing in plan one of the passage ways extending across the group of chambers and heating flues, with the cross-sectional areas of the different parts of the passage way indicated in a conventional manner.

Fig. 3 is a vertical longitudinal section of a battery of coke ovens showing a number of groups of coking chambers, heating flues and regenerators separated by partitions 57 in the end regenerators and subdivided in halves by partitions 18 in the middle regenerators, the direction of travel of the gases being indicated by arrows.

Fig. 4 is a similar view showing the gases travelling in opposite direction.

Fig. 5 is another transverse section of the oven showing a coking chamber, a regenerator below the same and the passage ways on top, with the coke oven gas, producer and waste gas mains arranged at the opposite corners of the regenerator.

Referring to the drawings, 8, 8 are supporting or pillar walls and 12, 12 are the regenerators separated by such walls and filled with checker work as usual. 10, 10 are the coking or distillation chambers arranged above the regenerators, the heating walls 9, 9 contiguous to these chambers being freely supported in a well known manner. Rows of vertical heating flues 11, 11 extending transversely of the oven intermediate each two coking chambers are in open communication with the regenerators, each regenerator serving two adjoining rows of heating flues. As shown in Figs. 2 and 3, partitions 57, 57, each extending lengthwise of a regenerator, subdivide the ovens of a battery into self-contained groups or units of eight complete coking chambers 10, one such chamber at either end belonging to two adjoining groups. Eight complete regenerators and two half regenerators at either end serve the nine rows of heating flues 11 extending intermediate the heating walls of the coking chambers. Vertical access flues 50 communicate with the rows of heating flues; sliding bricks 51 serve for varying the cross-sectional area of the exhaust, removable covers 55 close the upper ends of the access flues. A partition wall 18 extending lengthwise of the middle regenerator and transversely of the oven supports the middle coking chamber and subdivides the group into halves. Nine passage ways 14 extending on top of and across each group of ovens, the cross-sectional area of these passage ways increasing from the ends towards the mid-

dle as shown in Fig. 2^a. As shown in Fig. 1, each passage way communicates with three flues 11 out of each row of flues of a group, communication being established by way of the access flues 50 and short passages 53. The passage ways are arranged between the charging openings 15 (Fig. 5) of the coking chambers and past the gas outlets 16.

Figs. 3 and 4 show three and one half groups of ovens separated by partitions 57. The arrows show that the heating gases rise in the left hand halves, marked 1 and 5, of the first and third group (counting from the left) and in the right hand half, marked 4, of the second group, while they descend in the other halves. Thus, the adjoining halves (2 and 3 or 4 and 5 or 6 and 7) of adjoining groups are traversed by gases travelling in the same direction whereby the pressures on either side of the partitions 57 are approximately equal.

In preheating the air and gas, as required in heating with poor gas, where air and gas regenerators alternate with each other, I prefer disposing air regenerators on either side of the end partitions, these regenerators being supplied alternately with air and waste gas. I thereby prevent these partitions from getting in contact with the heating gases.

In order to provide for the circumstance that the coking chambers are not prismatic, but taper conically towards the side where the coke is expelled, whereby the quantity of coal to be distilled increases towards this side, I cause the heating of the walls to be increased towards this side in a predetermined manner. This is effected either by causing the cross-sectional areas of the passageways 14 to increase in proportion, as indicated in Fig. 5, or by correspondingly throttling the heating flues 11 by means of the sliding bricks 51. I thereby obtain a comparatively more vigorous heating towards the side of expulsion and a more uniform carbonization in the unit of time.

In order to provide for a uniform distribution of heat over the entire length of the coking chambers, in spite of the fact that the gas supply channel 56 (Fig. 1) now extends across the entire width of the oven, and in spite of the fact that the coking gas supply channels are liable to be clogged by the carbon separating out in consequence of the heavy hydrocarbons being decomposed at high temperatures, I so control the supply of air and gas, that on each reversal air is introduced from the side opposite to the entrance of the gas and under increased pressure, whereby the gas supply channel and the nozzles are cooled by the air.

In order to render possible the supply of heating gases and the exhaust of waste gas in accordance with the particular arrangement of groups of ovens, more espe-

ly when heating with strong gas diluted by smoke gas, I arrange at one side of the battery (Fig. 5) the waste gas main 19 communicating by bends 20 with channels 21 which is connected near the middle with the distributing main 23 by an opening 22. On the other side of the oven is disposed the air supply main 24 communicating by bends 25 with channel 26 which is connected by openings 27 with the distributing main 23. Sideways of the air supply main 24 is arranged the supply main 28 for the smoke gas designed to dilute the strong gas supplied from main 29, the poor gas main being marked 30. The channels 21 and 26 might as well be dispensed with, the bends 20 and 25 then giving directly into the distributing main 23. 40, 40 are the reversing valves controlling the strong gas main, 41 those of the poor gas main, 42 are the air reversing valves.

The oven is arranged for a selective operation with rich gas (which is the gas produced by distillation in the oven itself) or with a poor gas (producer gas or blast-furnace gas). Inasmuch as the poor gas has a lower heating value, it must be preheated in order to attain the flame temperature in the heating flues 11 which is necessary for the coking of the coal in the chambers 10. When operating the oven with rich gas, merely the air need be preheated.

To this end the regenerators 12 are connected each with two rows of heating flues 11 whereby it is possible to preheat the air as well as the poor gas in the checker work of the regenerators by alternately supplying the adjacent regenerators with air and with gas respectively.

In operating with poor gas the proportion of gas and air is about 1:1, so that the operator is at liberty to select any regenerator for the preheating of the gas. Preferably however, the bend 25 and the channel 30 connecting the air and gas flues with the regenerators 12 are arranged in such manner that on either side of the partition 18 (Fig. 2) only air or gases of combustion can be present, in order to prevent a combustible mixture to be formed in cases where a leakage should occur through the partition 18.

In operating the furnace with poor gas, at first one half of the regenerators belonging to a battery (Fig. 2) is supplied from below with gas and air which are preheated in contact with the checkerwork in the regenerators and enter the heating flues 11 where the combustion takes place. The gases of combustion now enter the passage ways 14 arranged in the top wall of the oven and flowing in the longitudinal direction of the battery are distributed onto the heating flues 11 of the other half 1. In the heating flues 11 of this group of chambers the gases flowing in downward direction enter the respec-

tive regenerators, whereby they transmit their heat to the checkerwork and thereafter escape through the distributing main 23 and channels 21 into the waste gas main. About every half hour the direction of flow is reversed.

When operating with rich gas the conditions of working are about the same, however in this case the regenerators merely serve for preheating the air, which then enters the heating flues 11. At the same time rich gas is supplied to the walls of these heating flues through the nozzles 52 and distributing main 56. Combustion of the mixture of the gas and preheated air now takes place in the heating flues 11. In all other respects the further travel of the gases is the same as described with reference to the operation with poor gas.

No matter whether the oven is operated with poor gas or with rich gas, the same quantities of waste gas are obtained by unit of time so that the velocity of flow of the gases in the heating flues, distributing mains and regenerators are the same in either case. If operating with rich gas, the proportion of gas and air is about 1:4, 5.

I wish it to be understood that I do not desire to be limited to the exact details of construction shown and described, for obvious modifications will occur to a person skilled in the art.

I claim:—

1. A coking retort oven comprising in combination, a series of coking chambers arranged side by side with the intermediate walls thereof common to the contiguous chambers, each of said walls containing a row of vertical combustion flues, regenerators underneath and communicating with said combustion flues at the bottoms thereof, a bus flue above said chambers and communicating with said combustion flues at the tops thereof and regenerator connection connecting at least four such rows of combustion flues to form a separate group or unit in such manner that flow may take place in one direction in all of the flues of all of the contiguous rows of combustion flues of one half of such rows of flues of said unit and in the opposite direction in all of the flues of the contiguous rows of combustion flues of the other half of the rows of combustion flues of the same unit.

2. A coking retort oven comprising in combination, a series of coking chambers arranged side by side with the intermediate walls thereof common to the contiguous chambers, each of said walls containing a row of vertical combustion flues, regenerators underneath and communicating with said combustion flues at the bottoms thereof, a bus flue above said chambers and communicating with said combustion flues at the tops thereof and regenerator connection

- connecting at least four such rows of combustion flues to form a separate group or unit in such manner that flow may take place in one direction in all of the flues of
- 5 all of the contiguous rows of combustion flues of one half of such rows of flues of said unit and in the opposite direction in all of the flues of the contiguous rows of combustion flues of the other half of the
- 10 rows of combustion flues of the same unit, the cross-sectional area of said bus flue increasing from the two ends towards the middle.
3. A coking retort oven comprising in combination, a series of coking chambers arranged side by side with the intermediate walls thereof common to the contiguous chambers, each of said walls containing a row of vertical combustion flues, regenerators underneath and communicating with said combustion flues at the bottoms thereof, separate bus flues above said chambers and communicating with said combustion flues at the tops thereof and regenerator connection connecting at least four such rows of combustion flues to form a separate group or unit in such manner that flow may take place in one direction in all of the flues of
- 25 all of the contiguous rows of combustion flues of one half of such rows of flues of said unit and in the opposite direction in all of the flues of the contiguous rows of combustion flues of the other half of the
- 30 rows of combustion flues of the same unit, the communication of each of said bus flues with said combustion flues being with the combustion flues of a single unit only, said retort comprising at least three of said units and partitions separating the regenerators
- 35 at both ends of an inner unit of said units from the regenerators in the adjoining units.
4. A coking retort oven comprising in combination, a series of coking chambers arranged side by side with the intermediate walls thereof common to the contiguous chambers, each of said walls containing a row of vertical combustion flues, regenerators underneath and communicating with said combustion flues at the bottoms thereof, separate bus flues above said chambers and communicating with said combustion flues at the tops thereof and regenerator connection connecting at least four such rows of combustion flues to form a separate group
- 45 or unit in such manner that flow may take place in one direction in all of the flues of all of the contiguous rows of combustion flues of one half of such rows of flues of said unit and in the opposite direction in all of the flues of the contiguous rows of combustion flues of the other half of the rows of
- 50 combustion flues of the same unit, the communication of each of said bus flues with said combustion flues being with the combustion flues of a single unit only, said retort comprising at least three of said units, partitions separating the regenerators at both ends of an inner unit of said units from the regenerators in the adjoining units, and means for causing the gases in the flues of said one half of such rows of flues of a unit to travel in the same direction as the gas in the flues of a contiguous said one half of such rows of flues of an adjoining unit, the cross-sectional area of each of said bus flues increasing from the two ends thereof toward the middle thereof.
- 55 7. A coking retort oven comprising in combination, a series of coking chambers arranged side by side with the intermediate walls thereof common to the contiguous chambers, each of said walls containing a row of vertical combustion flues, regenerators underneath and communicating with said combustion flues at the bottoms thereof, a bus flue above said chambers and communicating with said combustion flues at the tops thereof and regenerator connection
